CLAIM

The ornamental design for a container for breeding small animals, as shown and described.

DESCRIPTION

FIG. 1 is a front, side and top perspective view of a container for breeding small animals, showing our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is an exploded perspective view thereof.

1 Claim, 8 Drawing Sheets
